UNITED STATES PATENT OFFICE

148,860

DESIGN FOR A MEDALLION OR SIMILAR ARTICLE

Thomas H. Jones, Washington, D. C., assignor to the United States of America, as represented by the Secretary of War

Application September 23, 1947, Serial No. 141,552

Term of patent 14 years

(Cl. D29—19)

To all whom it may concern:

Be it known that I, Thomas H. Jones, a citizen of the United States and resident of the city of Washington, in the District of Columbia, have invented a new, original, and ornamental Design for a Medallion or Similar Article, of which the following is a specification, reference being had to the accompanying drawing, forming a part thereof.

Fig. 1 is a front view of a medallion, showing my new design.

Fig. 2 is a side view of the same.

It is understood that my design may be embodied in such articles as a medallion, medal, badge, plaque, or sign, without departing from the spirit of my invention.

The essential features of my design are shown in full lines.

I claim:

The ornamental design for a medallion or similar article, as shown and described.

THOMAS H. JONES.
